UNITED STATES PATENT OFFICE.

OSCAR E. A. WIESSNER, OF NEW YORK, N. Y.

DESIGN FOR AN END PIECE FOR BEDSTEADS.

SPECIFICATION forming part of Design No. 30,342, dated March 14, 1899.

Application filed February 16, 1899. Serial No. 705,732. Term of patent 3½ years.

To all whom it may concern:

Be it known that I, OSCAR E. A. WIESSNER, a citizen of the United States, and a resident of New York, (Brooklyn,) in the county of Kings and State of New York, have invented and produced a new and original Design for an End Piece for Bedsteads, of which the following is a specification.

The accompanying drawing, which forms a part of this specification, illustrates in elevation an end piece of a bedstead embodying my design, the principal features of the design being shown in full lines and the remainder of the end piece in dotted lines.

The leading or material feature of the design consists of the top rail A, provided with

two bowed portions B, one at each side of the middle of said rail. The remainder of the end piece consists of the usual side posts C and D, the bottom rail E, and a grill, as F, 20 and supports, as G, between the grill and the top rail.

I claim as my invention—

The design for an end piece of a bedstead, substantially as shown and described. 25

Signed at Brooklyn, in the county of Kings and State of New York, this 9th day of February, A. D. 1899.

OSCAR E. A. WIESSNER.
